UNITED STATES PATENT OFFICE.

EMMET T. WARREN, OF DYERSVILLE, IOWA.

FENCE-POST.

1,153,983.

Specification of Letters Patent. Patented Sept. 21, 1915.

Application filed March 6, 1915. Serial No. 12,573.

To all whom it may concern:

Be it known that I, EMMET T. WARREN, a citizen of the United States, residing at Dyersville, in the county of Dubuque and State of Iowa, have invented a new and useful Fence-Post, of which the following is a specification.

This invention relates to metal fence posts and means for attaching fencing thereto, one of the objects of the invention being to provide a post which can be formed readily from sheet metal, which has simple means for engaging the wires of a fence to hold them to the post and to prevent the wires from working upwardly or downwardly along the post as when the post is mounted on a hill or in a depression.

A further object is to provide fence holding means which is simple in construction, can be readily manipulated, but which cannot be easily displaced so as to release the wires.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown. In said drawings:—Figure 1 is a front elevation of a post embodying the present improvements, a portion of a fence being shown in position thereon. Fig. 2 is a section on line A—B Fig. 1. Fig. 3 is a section on line C—D Fig. 1. Fig. 4 is a section on line E—F Fig. 1. Fig. 5 is an enlarged vertical section through a portion of the post and showing one of the rod gripping lugs on the post.

Referring to the figures by characters of reference 1 designates a sheet metal post which is preferably triangular in cross section, the sides of the post converging upwardly. The longitudinal edges of the sheet from which the post is made are preferably disposed in lapped relation as shown at 2, it being understood, however, that when the post is driven into the ground the broad lower end thereof will tend to spread open in the ground thus to constitute an anchor which will serve to hold the

post securely in position. Formed within the front face of the post are longitudinal series of apertures 3, the two series being disposed out of alinement. Certain of the apertures, preferably the end and middle apertures of each series, are formed by striking ears 4 outwardly from the post, these ears having openings 5 therein disposed in alinement. The remaining openings of each series are formed by striking ears 6 from the post, each of these ears being formed with a slot 7 extending thereinto from the front edge thereof, the tongue 8 produced in the formation of the slot being bent downwardly to an inclined position and having its free end forked, as at 9. A retaining rod 10 is inserted downwardly into the openings 5 and slots 7 of the upper series, this rod having a radial arm 11 at its upper end adapted to be engaged by a fastening tongue 12 struck from the upper portion of the post, the said tongue being bent around the arm 11 as shown. Thus withdrawal of the rod 10 from the ears is prevented. When the rod is thus inserted it enters the forked ends 9 of the tongues 8, the said forked portions binding tightly against the rod as shown especially in Figs. 2 and 5. The ears of the lower series on the post likewise receive a retaining rod 13 having a radial arm 14 at its upper end. This radial arm extends under the lowermost ear 4 of the upper series and between the post 1 and the lower portion of rod 10 so as thus to be held against withdrawal from the post as long as the rod 10 is in position on the post.

After the post has been driven in the ground and become anchored in the manner hereinbefore pointed out, the fencing which can be a wire fabric 15, or separate wires 16, is placed against the post and between the ears 4 and 6. The lower rod 13 is then inserted downwardly through the ears 4 and 6 of the lower series after which the arm 14 is swung back against the post 1. The upper rod 10 is then inserted downwardly through its ears 4 and 6 until the arm 11 is brought above the tongue 12, whereupon said tongue is bent over and around the arm so as to hold the arm against movement. When the rod 10 is thus positioned, its lower end will lap the arm 14 and thus prevent removal of said arm 14 from under the lowermost ear 4 of the upper series. Thus it will be seen that the fencing will be held against movement away from

the post and, should the post be mounted in a depression, the strands of the fencing will not pull upwardly out of their proper positions but will, instead, press upwardly 5 against the inclined tongues 8 which will, in turn, deflect the strands back against the post 1 as will be seen by referring especially to Fig. 5. Should the post be erected on an elevation, the wires will pull downwardly on the ears 4 and 6 and thus be held 10 against downward displacement. It will be seen that the rods 10 and 13 cannot be removed unless some tool is employed for bending the tongue 12 out of engagement 15 with the arm 11. Thus the danger of injury to the fence by unauthorized persons is reduced to the minimum.

It will be noted by referring to the drawings that the ears 6 are not extended horizontally from the post but are inclined upwardly so that when a wire is supported by 20 one of these ears, it will be deflected inwardly into the angle formed between the post and the ear and thus be better supported than if it should be mounted on the outer portion of the ear.

What is claimed is:—

1. The combination with a metal post, of upper and lower non-aligning series of outstanding ears upon the post, certain of the 30 ears of each series having apertures therein, the remaining ears of each series having slots extending thereinto, a downwardly and outwardly inclined tongue extending below 35 each of said slots, a rod insertible through the apertures and slots in the ears of each series, a radial arm at the upper end of each rod, the lower portion of the upper rod constituting means for lapping the arm of 40 the lower rod, and means on the post for engaging the arm of the upper rod to hold said rod against removal from the ears.

2. The combination with a metal post, of upper and lower non-aligning series of 45 struck ears upon the post, certain of the

ears of each series having apertures therein, there being slots extending into the remaining ears of each series, inclined tongues extending from the slotted ears and partly under the slots, said tongues having forked terminals, a wire retaining rod insertible longitudinally through the apertures and slots in the ears of each series, a radial arm at one end of each rod, one end of one rod constituting means for lapping the arm of 55 the other rod thereby to hold said arm in position under one of the ears to prevent withdrawal of the rod, and means outstruck from the post for engaging the arm of the other rod to hold said rod against withdrawal from its ears.

3. The combination with a metal post, of upper and lower non-aligning series of outstruck ears upon the post, certain of the ears of each series having apertures therein, there being slots extending into the remaining ears of each series, inclined tongues extending from the slotted ears and partly under the slots, said tongues having forked terminals, a wire retaining rod insertible longitudinally through the apertures and slots in the ears of each series, a radial arm at one end of each rod, one end of one rod constituting means for lapping the arm of 65 the other rod thereby to hold said arm in position under one of the ears to prevent withdrawal of the rod, means upon the post for engaging the arm on the other rod to hold said rod against withdrawal from the ears, the forked terminals of the tongues 70 constituting means for frictionally engaging the respective rods.

In testimony that I claim the foregoing as my own, I have hereto affixed my signature in the presence of two witnesses.

EMMET T. WARREN.
